CASING OR CABINET STRUCTURE FOR WATER HEATERS AND THE LIKE

Clarence H. Morrow, Shaker Heights, Ohio, assignor to The Hotstream Heater Company, Cleveland, Ohio, a corporation of Ohio

Application February 25, 1938, Serial No. 192,449

3 Claims. (Cl. 122—494)

This invention relates to improvements in casing or cabinet structures for water heaters or the like.

The general object of the present invention is the provision, for a water heater or the like, of a casing or cabinet structure which includes a minimum number of exceptionally sturdy parts capable of being economically manufactured and readily assembled, with the result that the present casing or cabinet structure is of inexpensive form and of exceptionally rugged character.

A more specific object of the present invention is the provision of a casing or cabinet structure for a water heater in which the burner thereof is located relatively close to the floor or other surface upon which the casing or cabinet structure rests, and which casing or cabinet structure is of such construction that the temperature at such floor or other surface is effectively held below the degree specified by building codes and the like, even during prolonged periods of operation of such burner.

Another more specific object of the present invention is the provision of a water heater casing or cabinet structure in which the flue opening and the water and fuel pipe openings may be provided either in the top wall thereof or in the side wall thereof, the latter location of such openings leaving the top wall of the casing or cabinet structure of imperforate character for "table top" use, as will hereafter more fully appear.

Other objects of the present invention are in part obvious and in part will appear more in detail hereinafter.

The present invention will be readily understood from the following description of two embodiments thereof, reference being had to the accompanying drawings, in which

Fig. 1 is a front view of a water heater having a casing or cabinet structure embodying the present invention; Fig. 2 is a top plan view thereof; Fig. 3 is a vertical sectional view thereof, on the line 3—3, Fig. 1; Fig. 4 is a horizontal sectional view thereof, on the line 4—4, Fig. 3; and Fig. 5 is a vertical sectional view of the upper portion of a water heater having a casing or cabinet structure embodying a modified form of the present invention.

Before the present invention is described in detail, it is to be understood that such invention is not limited to the details of construction and/or the specific arrangement of parts herein illustrated and/or described, as the invention obviously may take other forms. It also is to be understood that the phraseology or terminology

herein employed is for the purpose of description and not of limitation, inasmuch as there is no intention and no desire to limit the present invention, as herein disclosed and as defined in the appended claims, beyond the requirements of the prior art.

Although certain features of the present invention are applicable to casing or cabinet structures generally, the casing or cabinet structure constituting such invention is particularly adapted for water heaters. For the disclosure of the present invention, therefore, two water heater casing or cabinet structures embodying such invention are here illustrated, with such water heater parts diagrammatically illustrated and/or described as are necessary or desirable to enable the invention to be fully understood.

In the accompanying drawings, 10 indicates the water reservoir of a water heater, the generally cylindrical metal side wall 11 of which reservoir 10 may, and here does, extend therebelow. To prevent heat loss, suitable insulation is provided for such reservoir, and in the embodiments of the invention here illustrated, suitable insulation 12 is wrapped around the reservoir side wall 11, including its depending extension, and for the protection and maintenance of such insulation, an enclosing metal shell may be provided therefor, if desired. Suitable insulation 13 is also provided for the upper end of the water reservoir 10, such as rock wool insulation or the like placed upon the crowned top wall of the reservoir, within the extended upper end of the insulated reservoir side wall 11. If desired, simple metal cover member 15 may be provided for the upper end of the reservoir, as here shown and as will be readily understood.

Within the depending extension of the water reservoir side wall 11, and between the reservoir base plate 16 and a transverse metal partition member 17 to be hereinafter referred to, is a chamber 18 for the burner 19 of the water heater, said burner being of any suitable form and with which may be used any suitable type of fluid fuel, such as gas. Inasmuch as the fuel supply means 45 for such burner, and the various controls therefore, such as thermostats, etc., constitute no part of the present invention, they are not here shown. They may, if desired, be of the character and have the arrangement shown in my co-pending 50 application for a Water heater, application Serial No. 73,510, filed April 9, 1936. So far as this invention is concerned, it is sufficient to here point out that a compartment 20 is provided in the present casing or cabinet structure, between the 55

front portion of the side wall thereof and the insulated water reservoir side wall, and that in such compartment, the fuel supply pipes, controls, etc. may be arranged, a suitable opening 22 being provided in the insulated depending extension of such reservoir side wall for the extension of the burner fuel supply pipes, etc.

Communicating with the burner chamber 13 and extending upwardly through the water reservoir 10 is a suitable flue pipe 24 for the products of combustion formed in such chamber. Communicating with the water reservoir 10 is a cold water inlet pipe 25 and a hot water withdrawal pipe 26, as is usual.

15 The casing or cabinet structure constituting the present invention is of exceedingly simple and of exceptionally rigid character, and comprises a minimum number of inexpensively formed parts which are capable of being easily and quickly assembled.

In both of the embodiments of the invention here illustrated, the casing or cabinet structure includes a simple one-piece side wall and base member A, economically and conveniently formed 25 as a metal stamping and bent to provide a side wall and a base, the side wall comprising a front portion 30, side portions 31 and 32, and a rear portion 33. The longitudinal edge portions of such member A are interconnected or joined in any suitable manner, such as by the simple but effective lock seam 35 here shown, said seam forming a part of the rear side wall portion 33 of the casing or cabinet structure so that such seam is not normally exposed to view.

35 As best shown in Figs. 1 and 4, the front portion 30 of the one-piece side wall and base member A is provided with a suitable door opening 38 and with inwardly extending flanges surrounding such opening, there being at the top of said 40 opening an inwardly extending flange 39 which terminates in a short depending shoulder 40; at the bottom of said opening an inwardly extending flange 41; and at the two sides of said opening inwardly extending flanges 42 which terminate in relatively short and laterally disposed converging shoulders 43. The door 45 for such 45 door opening 38 is here shown as a simple one-piece metal stamping, with inturned edge flanges, there being an inturned top flange 46 and in-turned side flanges 47, for cooperation respectively with the front wall flange shoulders 40 and 43 in limiting inward movement of such door, and an inturned bottom flange 48 having a depending extension 49 for hooking cooperation 50 with the front wall bottom flange 41 in securing the bottom portion of the door in closing position. For releasably securing the top portion of said door in closing position, any suitable means may be utilized, the means here shown 55 for such purpose including a headed element 50 secured to the door on the inner surface thereof and just below its top edge flange 46 and resilient arms 51 mounted either on the front wall top flange shoulder 40 or on a suitable metal strip secured thereto for the releasable retention of such headed element, all as will be readily understood.

For the venting of the compartment 20 of the casing or cabinet structure, suitable louvers 53 70 are here provided in the door 45, one in its upper end portion and two in its lower end portion, said louvers also serving as a limited secondary air supply for the burner 19.

The base of the one-piece side wall and base member A includes four downwardly and inward-

ly inclined base portions, there being an inclined front base portion 55 which constitutes a depending extension of the front wall portion 30, two inclined side base portions 56 and 57 which respectively constitute depending extensions of the side wall portions 31 and 32, and an inclined rear base portion 58 which constitutes a depending extension of the rear wall portion 33. As best shown in Figs. 1 and 3, each of said inclined base portions is here integrally provided at its lower end with an inwardly extending horizontally disposed flange 60 having a relatively short upturned inner end 61. The four flanges thus formed rest upon the floor or other surface upon which the casing or cabinet structure is supported, and the width of said flanges is such that they define, at such floor or other surface, a centrally disposed base opening 64. In stamping the one-piece side wall and base member A, generally triangular notches are formed therein between those parts thereof which constitute the base portion of such member, as will be readily understood, so that after such member has been bent into its proper shape and the longitudinal edges thereof suitably joined or interconnected, as at 35, the adjacent side edges of the four inclined base portions (55, 56, 57 and 58) and the adjacent side edges of the flanges 60 thereof, including their upturned inner ends 61, are welded or otherwise rigidly secured together or interconnected.

Horizontally arranged within the base part of the side wall and base member A, above and co-extensive with the centrally disposed base opening 64 thereof, is a metal supporting plate 66 35 having a depending peripheral flange 67 which rests upon the horizontally disposed interconnected base flanges 60, with the consequent closing of the base opening 64. As here shown, the depending peripheral flange 67 of said supporting plate is provided with a horizontally disposed inward extension 68 for seating engagement upon the correspondingly disposed base flanges 60, and if desired, the base of the present casing or cabinet structure may be made more rigid, and hence 45 more rugged, by welding or otherwise suitably connecting the inward extension 68 of said supporting plate 66 to such base flanges 60. As here shown, the inner end 69 of such extension 68 is turned upwardly, and such upturned end 50 is welded or otherwise rigidly connected with the upturned inner ends 61 of the base flanges 60, thereby providing a casing or cabinet structure having a base of particularly strong and sturdy character.

Arranged above, and generally parallel with, the supporting plate 66 is the metal partition member 17 heretofore referred to and which constitutes the bottom wall of the burner chamber 18. As shown, said partition plate rests upon 60 and is maintained in spaced relationship relative to such supporting plate 66 by suitable spacing means, the means here shown comprising two metal channel bars 73, one lying upon and extending along each side edge portion of such 65 supporting plate 66.

As best shown in Figs. 1 and 3, the channel bars 73 are located beneath the annular side wall 11 of the water reservoir 10, and such bars thus serve to distribute the weight of such reservoir 70 over the supporting plate 66, with the effective transmission of such weight to the rigidly connected base portions of the casing or cabinet structure.

To simplify the assembly of the present water 75

heater, the channel bars 73 may be welded or otherwise suitably secured to the partition member 17, and such bars and partition member are preferably secured to the depending extension of the insulated side wall 11 of the water heater reservoir. For such purpose, suitable bolts 14 extend through the two channel bars 73, through the partition member 17, and through suitable clips or brackets 75 secured to such reservoir wall extension, all as clearly shown in the accompanying drawings.

As clearly shown in Fig. 4, the two side edges of the partition member 17 engage the side wall portions 31 and 32 of the side wall and base member A, and the rear edge of said partition member engages the rear wall portion 33 of such wall and base member, the effect of which is to tightly close the burner chamber 18 at its bottom. The front edge of said partition member 17 does not engage, however, the front wall portion 30 of the side wall and base member A, but terminates short thereof, with the result that an elongated opening 78 is provided at the front of such partition member through which secondary air for the burner 19 may flow from the space 80 between said partition member and the supporting plate 66 therebelow. For the supply of air to the space 80, suitable air inlet openings 81 are provided in the inclined rear base portion 58 and in the rear end part of each of the inclined side base portions 56 and 57, as best shown in Fig. 4.

As a result of such a construction, secondary air for the burner 19 flows through the inlet openings 81, at the rear of the base of the present casing or cabinet structure, to the space 80 between the supporting plate 66 and the partition member 17, and thence through the elongated opening 78 at the front of the base to the inlet opening 22 of the burner chamber 18, said burner chamber inlet opening being in the depending extension of the insulated wall 11 of the water reservoir 10, as heretofore pointed out. The flow of this relatively cool air across the supporting plate 66 effectively cools the floor or other surface therebelow, so that the temperature at such floor or other surface does not rise above the degree specified by building codes, etc., even during prolonged or extended periods of operation of the burner 19. The space below the supporting plate 66 or, in other words, the space between such plate and the floor or other surface upon which the casing or cabinet structure rests, is a dead air space, which also aids in maintaining the temperature at such floor or other surface at a sufficiently low degree for complete safety, etc.

By making the base portions 55, 56, 57 and 58 of the casing or cabinet structure of downwardly and inwardly inclined form, the general appearance of the casing or cabinet structure not only is improved but also, additional toe room is provided at the base thereof. The location of air inlet openings 81 in the inclined rear base portion 58, a location most remote from the elongated air opening 78 at the front part of the base of the casing or cabinet structure, not only insures the maximum length of flow of the air entering such openings, with a consequent maximum cooling effect upon the supporting plate 66 and the floor or other surface therebelow, but also insures a proper flow of air at all times through such openings 81, even though the rear side wall of the casing or cabinet structure is

placed close to or adjacent the vertical wall of a room, as is usual.

The top of the water heater casing or cabinet structure, as disclosed in Figs. 1 to 4 inclusive, is a simple one-piece metal stamping 90 having a depending peripheral flange 91, the lower end portion of which is telescopically associated with the upper end portions of the four upright side wall portions of the casing or cabinet structure, that is, with side wall portion 30, 31, 32 and 33 of the one-piece sheet metal member A.

As will be readily understood, the depending peripheral flange 91 of the top member 90 may be of straight form, or of any other suitable form, such as the form here shown, in which the upper portion of such flange is of outwardly and downwardly inclined form and the bottom portion thereof is of straight form, for convenient telescopic relationship with the front, rear and side wall portions of the casing or cabinet structure.

In this embodiment of the invention, the embodiment of Figs. 1 to 4 inclusive, the flue pipe 24, the water pipes 25, 26, and the fuel supply pipe (not shown), extend through the top of the casing or cabinet structure, so that the top member 90 thereof is provided with suitable openings therefor. No opening is here shown for the fuel supply pipe but a flue pipe opening 94 and water pipe openings 95 and 96 are shown, the opening 95 being for the cold water supply pipe 25 and the opening 96 being for the hot water withdrawal pipe 26, all as will be readily understood.

In the embodiment of the invention illustrated in Fig. 5, the water heater flue opening 94a, the water pipe openings 95a, 96a, and the gas-supply pipe opening (not shown), are located in the rear wall portion 33a of the casing or cabinet structure, and the top thereof is of flat imperforate form so that it may be conveniently used as a table top, the height of this casing or cabinet structure being substantially that of the ordinary table.

In the embodiment of the invention illustrated in Fig. 5, a plain sheet metal member 98 covers the top opening provided by the front, rear and side wall portions of the casing or cabinet structure, with the depending peripheral flange 99 of such member 98 telescopically associated with the upper end portions of said wall portions and thus serving as a means to maintain them in proper position relative to one another. Suitably secured to the member 98 is the top member 100 of this casing or cabinet structure, and such top member may be provided, if desired, with a porcelain or enameled exterior. The top member 100 here shown is provided with a depending peripheral flange 101 having an in-turned lower end 102, and arranged within such top member and extending along two sides thereof and held in place by the inturned lower end of the peripheral flange thereof are two strips or rails 103, of wood or the like, and to which is secured, such as by screws 104, the sheet metal member 98. As a result, no strains are created in the top member 100, either in the assembly thereof or later, which might crack or otherwise mar the porcelain or enameled exterior thereof, all as will be readily understood.

To protect from heat that part of the lower end portion of the door 45 which is located directly opposite or in front of the opening 22 for the burner chamber 18, a suitable metal protecting strip 110 may be provided for such door part.

- The metal strip 110 here shown in Fig. 3, has its lower end portion welded or otherwise suitably secured to the depending extension 49 of the door bottom flange 48 and has its forwardly offset upper end portion welded or otherwise suitably secured to an intermediate portion of the door, with the consequent protection of that part of said door which lies directly in front of the burner chamber opening 22.
- 10 Other features and advantages of the present invention will readily occur to those skilled in the art to which it relates.
- What I claim is:
1. In a casing or cabinet for a water heater or the like having a burner chamber provided with an air inlet and with a bottom wall, a side wall structure having a bottom opening and adapted to surround said water heater or the like and to rest upon a floor or other supporting surface, and a closure member for said bottom opening, the central portion of said closure member being spaced from said side wall structure and being located between and spaced from said floor or other supporting surface and said burner chamber bottom wall by a depending peripheral flange with which said closure member is provided, said closure member flange having sealing engagement with the lower end of said side wall structure around the bottom opening thereof, the lower end portion of said side wall structure being provided with air inlet means remotely located relative to the burner chamber air inlet, whereby air entering the inlet means of said side wall structure travels to said burner chamber air inlet around the depending flange of the closure member and also between the central portion of said closure member and said burner chamber bottom wall, with a resultant cooling effect upon said floor or other supporting surface.
  2. In a casing or cabinet structure for a water

heater, said water heater having a water reservoir and having a burner chamber with a sheet metal bottom wall, enclosing wall means for said water heater extending below said bottom wall and there having downwardly and inwardly inclined end portions adapted to rest upon a floor or other supporting surface, a substantially imperforate sheet metal closure member having a top wall spaced below said bottom wall and having a continuous edge flange turned substantially vertically downward, said edge flange being there attached to said end portions of said wall means, members supporting said reservoir, said last-named members resting on said closure member directly over its flange, and said last named members serving to space said closure member top wall and said burner chamber bottom wall.

3. In a casing structure for a water heater or the like having a burner chamber provided with an air inlet and with a bottom wall, a combined side wall and base comprising enclosing wall means for said water heater extending below and beneath said bottom wall and there provided with portions for contact with a floor or other supporting surface, said wall means having adjacent and continuous with said floor supporting portions a central portion spaced above the floor and spaced below said bottom wall, and said wall means below and beneath said bottom wall forming a substantially continuous and imperforate casing except that the lower end portion of said wall means is provided with air inlet means remotely located relative to said burner chamber air inlet, whereby air entering said air inlet means and traveling to said chamber air inlet passes over said floor contacting portions and between said central portion and said bottom wall with a resultant cooling effect.

CLARENCE H. MORROW. 40
